UNITED STATES PATENT OFFICE.

CHARLES J. T. CORDES, OF WALDWICK, NEW JERSEY.

MOLDING APPARATUS.

1,188,415.

Specification of Letters Patent. Patented June 27, 1916.

Application filed February 25, 1911. Serial No. 610,802.

To all whom it may concern:

Be it known that I, CHARLES J. T. CORDES, a citizen of the United States, and a resident of Waldwick, in the county of Bergen and State of New Jersey, have invented certain new and useful Improvements in Molding Apparatus, of which the following is a specification.

In a prior patent granted to me October 10, 1907, No. 869,828, I have disclosed apparatus for making building blocks particularly adapted for forming blocks of a type in which each block is divided and has an air-space therein adapted to form with corresponding air-spaces of other blocks a continuous air-space when such blocks are assembled and cemented together to form a complete wall, the two parts of the individual blocks of this type being illustrated in 15 said patent as held together by tie-pieces or anchor-bars formed in the block in the process of molding the same in the apparatus.

The present invention is intended for the making of blocks of the same general type 20 and is directed particularly to the mold proper; and the principal object of the invention is to provide an improved molding apparatus for positively centering the tie-pieces or anchor-bars in the mold in forming 25 divided blocks of the character just described containing air-spaces separating different parts of such blocks.

In the drawings Figure 1 is a plan with parts broken away of a molding apparatus 30 illustrating my present invention. Figs. 2-10 inclusive are details of various kinds of anchor-bars, cores and blocks used or made in such a machine.

Similar characters designate like parts in 40 all the figures of the drawings.

The principal members of the mold will usually be, as in my aforesaid patent, two end walls, two side walls and a bottom wall. In the construction illustrated the end walls 45 may be of the type indicated at 4 and 5 and the side walls of the types illustrated at 6 and 7, each being a stiff plate movable in and out to close and open the mold, and all coöperating with a suitable bottom wall 3. This bottom wall is intended to move up and down 50 in a rectangular frame 3'.

The end walls may be moved in and out by suitable operating connections indicated at 57 and 60.

Blocks of many different kinds, differing in size, form, structure, etc., may be made

in the mold illustrated herein. For molding blocks having air-spaces and consisting of a plurality of parts secured together by tie-pieces or anchor-bars, cores will be employed in connection with the walls of the mold just described. Here a four-part core is illustrated, the main or center core-piece being indicated at 72 and the two end core-pieces at 73 and 74. The end core-pieces are 60 intended to be secured to the end walls 4 and 5 of the mold, and the main or center core-piece is intended to be secured to the bottom wall of the mold. Moreover, the block to be molded will be formed around said core and 65 preferably on a flat pallet or board, of any proper size and shape, placed on the rectangular support 3'. With the cores shown, the pallet should have a central opening corresponding in size and shape to the cross-section 70 of the core at the bottom of said core. The central core-piece 72 fastened to the bottom wall of the mold will of course move up and down with such wall as the mold is 75 opened and closed. In this case, however, the whole of the central core-piece is not drawn out when the bottom wall descends, said core being illustrated as tapered toward the center from the bottom and top thereof and made in two parts, the upper of 80 which may be withdrawn by an upward movement in any suitable manner. This permits a block to be molded with a central opening or air-space which tapers toward the center of the block from both the 85 top and bottom thereof. The upper section of the central core-piece is indicated at 72'.

The principal feature of the molding apparatus shown is the provision of means for 90 positively locating the tie-pieces or anchor-bars of divided building blocks in such a manner as to prevent displacement of the anchor-bar while the blocks are being formed. In order to accomplish this I prefer to make use of core-pieces having in 100 their meeting faces horizontal anchor-bar channels with offset portions, such as vertical recesses, intersecting them for the purpose of preventing lateral movement of correspondingly shaped anchor-bars, that is, of 105 anchor-bars having lateral ears or projections of such construction that said bars substantially fit the channels and recesses in the meeting faces of the core-pieces and are held by the walls of such recesses against lateral 110 movement, that is, movement endwise of the anchor-bar. Fig. 2 illustrates the meeting

face of one of the core-pieces 74 and the channels and recesses formed therein and shaped to fit an anchor-bar 75, from which project ears or lugs 76 fitting the recesses in 5 the face of said core-piece. This core-piece has the same shape in cross-section as the main core-piece illustrated in Fig. 1. This shape does not interfere with its being drawn from the block by movement length- 10 wise of the mold of the end-wall to which it is secured. Fig. 3 illustrates one form of building-block 77 formed in the mold and having embedded therein an anchor-bar of the type shown at 75 in Fig. 2, the air-space 15 78 in the block being one having walls tapering from the top and bottom toward the center of the block. In this block the anchor-bar is positively positioned and centered, it being impossible for it to be 20 displaced when held in the manner shown in Fig. 2.

Fig. 4 illustrates a modification of the invention in which a two-part anchor-bar is employed, these parts being symmetrically 25 formed, as shown at 75', so that two may be used together at the vertical center of the building-block and the two halves of the two-part anchor-bar used near the bottom and top respectively of the block.

30 Figs. 5 and 6 illustrate in side elevation and in transverse section the details of construction of a modification of the two-part center core-piece 72--72' shown in the main views, the manner in which the upper half 35 72' of the center core-piece is recessed to form a handle for lifting it out of the block being clearly illustrated in these views and in Fig. 2. These views also illustrate at 40 79 how a channel and locking recess are formed in the upper meeting face of the lower member 72 of the center core-piece in a manner similar to that in which such channel and recess are formed in an end core-piece. Fig. 7 shows an underside view of 45 the lower half 72 of the center core-piece.

Fig. 8 illustrates a modification of the invention in which the end core-piece 74 has horizontal channels and locking recesses near the upper and lower sides thereof in 50 which are positively located the two halves

75' of the two-part anchor-bar shown in Fig. 4, this being a variation of the mode of using the anchor-bars.

Fig. 9 illustrates still another means for tying the two parts of a divided building-block together, the device shown being a tie-frame 80 rather than an anchor-bar. It consists of two longitudinal members and two transverse cross-bars or anchor-bars each of which cross-bars has a projecting lug or ear 60 81 for locating the tie-frame in a central position with respect to the core-pieces of Figs. 5, 6 and 7.

What I claim is:

1. A molding apparatus comprising side 65 and end walls and a bottom wall, in combination with a core having a plurality of core-pieces, two of which are end core-pieces secured to said end walls and one of which is a main core-piece secured to said bottom 70 wall, said core having in the meeting planes of said main and end core-pieces anchor-bar channels with offset portions positioned and constructed to receive and prevent endwise movement of corresponding anchor-bars having projecting ears constructed to lie in the offset portions of said channels. 75

2. A molding apparatus comprising side and end walls and a bottom wall, in combination with a core having a plurality of 80 core-pieces, two of which are end core-pieces secured to said end walls and one of which is a two-part main core-piece divided horizontally and the lower part of which is secured to said bottom wall, said core having in the meeting planes of said main and 85 end core-pieces anchor-bar channels with offset portions positioned and constructed to receive and prevent endwise movement of corresponding anchor-bars having projecting ears constructed to lie in the offset portions of said channels. 90

Signed at New York, in the county of New York and State of New York, this 24th day of February, A. D. 1911.

CHARLES J. T. CORDES.
